UNITED STATES PATENT OFFICE.

HENRY W. MANSUR, OF BOSTON, MASSACHUSETTS.

DESIGN FOR A HOPPER FOR CLOSETS.

SPECIFICATION forming part of Design No. 16,139, dated June 30, 1885.

Application filed April 18, 1885. Term of patent 14 years.

To all whom it may concern:

Be it known that I, HENRY W. MANSUR, of Boston, in the county of Suffolk and State of Massachusetts, have originated and invented a new and useful Design for Hoppers for Water-Closets; and I do hereby declare that the following is a full, clear, and exact description thereof, reference being had to the accompanying drawings, forming a part of this specification, in which—

Figure 1 is a plan view, and Fig. 2 is a vertical section.

This design has relation to hoppers for water-closets; and it consists in the novel form and configuration thereof, as herein shown and described.

In the accompanying drawings, illustrating this design, the letter A designates the hopper, having the ellipsoidal cavity B, whereof the horizontal elements from the upper portion to the opening or mouth C of the tubular portion D are elliptical and arranged with reference to an oblique central line indicated by dotted lines at E, said line being inclined forward and upward. This design provides an ellipsoidal cavity, whereof the horizontal elliptical elements trend forward from the lower to the upper portion, whereby the rear portion of the curved wall is made nearly vertical, and this curved wall as it extends forward expands outward and upward, gradually becoming larger, so that the walls increase in obliquity from the rear forward or more

vertical portion forward. The upper portion of the wall of the hopper is curved upon concave lines in vertical section, and the lower portion of said wall, which merges into the wall of the tubular portion, is in similar section curved upon convex lines. The upper portion of the hopper is formed with an inwardly and downwardly extending skirt-flange, as indicated at F, said flange extending around the upper portion in elliptical form, corresponding to that of the upper portion of the body of the hopper.

Having described this design, what I claim, and desire to secure by Letters Patent, is—

The design for a water-closet hopper wherein the bowl or hopper gradually expands from the tubular discharge portion in ellipsoidal form, the horizontal elliptical elements having their centers in an oblique line extending upward and forward from the center of the mouth of the tubular portion, and the wall of which is, from above downward, concave in its upper portion and convex in the lower portion, which merges into the wall of the tubular portion, as shown and described.

In testimony that I claim the foregoing as my own I affix my signature in presence of two witnesses.

HENRY W. MANSUR.
